UNITED STATES PATENT OFFICE.

ERNEST J. SMITH, OF LONDON, ENGLAND, ASSIGNOR TO GOSS PRINTING PRESS COMPANY, OF CHICAGO, ILLINOIS, A CORPORATION OF ILLINOIS.

STEREOTYPE-PLATE-CASTING MACHINE.

Application filed December 24, 1920. Serial No. 433,022.

To all whom it may concern:

Be it known that I, ERNEST J. SMITH, a subject of the King of Great Britain, residing in London, England, have invented 5 certain new and useful Improvements in Stereotype-Plate-Casting Machines, of which the following is a specification.

The invention relates to a novel stereotype plate casting machine, and more especially to novel features and structures in 10 such a machine cooperating together to constitute improvements in construction and in the manner of operation.

Objects and advantages of the invention 15 will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

25 The accompanying drawings, referred to herein and constituting a part hereof, illustrate one embodiment of the invention, and together with the description, serve to explain the principles of the invention.

30 Of the drawings:

Fig. 1 is a side elevation of a stereotype plate casting machine embodying the invention, and showing the mechanism in plate casting position;

35 Fig. 2 is a view similar to Fig. 1, but showing the mechanism in plate delivery position;

40 Fig. 3 is a section, taken substantially on the line 3-3 of Fig. 2, but omitting any showing of the concave casting member;

45 Fig. 4 is a section taken substantially on the line 4-4 of Fig. 2, and showing the casting core partly in section and partly in elevation;

50 Fig. 5 is a detail in plan of certain of the parts shown in the upper left hand part of Fig. 3, and showing the holding means for the casting core in engagement therewith;

Fig. 6 is a detached detail of the mechanism for operating the movable back of the concave casting member to strip the matrix

from the cast plate, and showing the parts in casting position;

55 Fig. 7 corresponds to Fig. 6, but shows the parts in matrix stripping position;

Fig. 8 is an enlarged detail, with parts in section, of the actuating lever for the mechanism shown in Figs. 6 and 7;

60 Fig. 9 is a detached plan of part of the core rotating mechanism shown at the top of Fig. 4;

Fig. 10 is a horizontal section taken on the line 10-10 of Fig. 4;

65 Fig. 11 is a greatly enlarged fragmentary detail of the operating mechanism for the core holding detent shown in Figs. 3 and 5;

Fig. 12 is a horizontal section, on an enlarged scale, taken on the line 12-12 of Fig. 1; and

70 Fig. 13 is a fragmentary, longitudinal, sectional detail of the core wall which casts the ribs on the back of the plate.

The invention in the embodied form is 75 exemplified in a stereotype plate casting machine having the casting members consisting of a vertical rotatable core and a concave or drag, the drag rocking from the vertical casting position through a vertically disposed arcuate path down to an inclined position, rendering the changing of matrix sheets both easy and rapid.

80 The invention provides for the stripping of the matrix from the cast plate before, and preparatory to, the movement of the drag or concave away from the casting position and prior to the rotation of the core to remove the plate from casting position.

85 In the embodied form of such matrix stripping means the matrix holding clamps are mounted on a part of the drag which is backwardly and forwardly movable relatively to the remainder of the drag, that is, the matrix sheet carrying part is independently movable toward and away from casting position. The mechanism is shown operated by hand actuated means.

90 The cast plate is moved longitudinally of the core to remove it primarily from the casting position and to bring it into operative relation to the means for cutting off the riser, and later for delivery from the machine.

95 The embodied form of such means com-

prises a device engaging with the cast plate and lifting it longitudinally of the casting core, that is, a portion of the wall of the casting chamber is shaped so that the plate will cast in engagement therewith, that portion thereafter moving vertically and taking the plate with it. This operation is rendered automatic and is called into action by the movement of the drag away from casting position.

The invention comprises also power operated means for rotating the core to bring a plate from casting position to delivery position, this operating automatically concurrently with the removal of the drag from casting position just after the plate is cast.

In accordance with one feature of the invention, the various functions of the machine, such as swinging of the drag between its two positions, lifting of the plate along the core after being cast, rotation of the core, and cooperating functions are controlled by a single manually operable lever; and preferably there are a plurality of such levers any one of which can be operated for the purpose stated.

The foregoing features of the invention will be detailed hereinafter, and other features of the invention will be first set forth in connection with the following detailed description of the present preferred embodiment, the foregoing general and the following detailed description being, it will be understood, exemplary and explanatory of the invention and not unnecessarily restrictive thereof.

In the embodiment of the invention illustrated by way of example in the accompanying drawings, a casting machine is provided with a vertically disposed, rotatable core 1 and cooperating therewith a concave or drag 2 swinging backwardly from the core in a vertically disposed arcuate path.

In the embodied form, the concave or drag 2 is provided with a matrix carrying back 3, which is movable relatively to the remainder of the drag at the casting position to strip the matrix from the cast plate preparatory to the drag being swung backwardly from casting position. The plate is then moved from the casting position to the delivery position while carried by the rotating core, the plate x being removed from the core in a direction longitudinal to the axis of the core.

Referring now to the specific mechanism for rocking the drag or concave 2 to and from casting position, in the embodied form thereof the means for so moving the concave 2 to and from casting position (Figs. 1, 2 and 3) and the means for moving the matrix carrying back relatively to the rest of the concave casting member (Figs. 1, 2, 3, 6 and 7) cooperate together, and are also structurally connected together.

Referring first to the means for rocking the concave member 2 in its vertically disposed arcuate path to and from casting position, arms 5 and 6 are fixed to a shaft 7, which shaft is journaled in the side frames 8 and 9 of the machine. Thus arms 5 and 6 have a rocking motion in connection with the mechanism to be later described.

Supported in the arms 5 and 6 is a shaft 10, held in position in the arms by end collars 11 and 12, which are fixed to the shaft. For the purpose of imparting swinging movement to the shaft 10 about the shaft 7, two links 13 and 14, respectively, are mounted at either side upon shaft 10, and are connected, respectively, to arms 17 and 18. Arms 17 and 18 have their respective hubs fixed to a shaft 20, which shaft is journaled in the machine frame. Links 13 and 14 are provided, if desired, with adjustment devices, such as turn-buckles 15 and 16, respectively.

Fixed on the shaft 20, at either end thereof, are two crank arms 21 and 22, provided, respectively, with handles 23 and 24, which serve to rock the shaft 20 and thereby, through the connections described, to rock the shaft 10 about the shaft 7.

The concave 2 is connected to the shaft 10 so that the rocking of the shaft 10, just referred to, will carry the drag or concave 2 to and from casting position. As embodied, the concave 2 has fixed thereto and projecting backwardly therefrom two arms 27 and 28, having their respective hubs 29 and 30, journaled upon the shaft 10. Spacing collars 31 and 32 are also shown fixed to shaft 10.

Means are also provided for so swinging the concave 2 from the other end of the machine (Figs. 1, 2 and 3), and as embodied, the end of the shaft 20 is provided with a sprocket wheel 35, over which runs an endless sprocket chain 36. Sprocket chain 36 also runs over a sprocket wheel 38, which wheel is journaled in the part 39 of the machine frame. Fixed to the shaft 40 of the sprocket wheel 38 is an arm 41, having a handle 42, similar to the handles 23 and 24, and connected thereto as described. Thus by rocking the arm 41, through the connections described, shaft 20 is rocked, and thereby the concave 2 is swung to and from casting position. The operation of the parts in effecting this movement will be understood from Figs. 1, 2 and 3.

Means are provided for stripping the matrix from the cast plate at the casting position (Figs. 1, 2, 3, 6, 7 and 12), so that the matrix will be free from the plate before the plate is carried away by the core. The matrix, of course, is mounted upon and travels with the drag or concave 2. In the embodied form of said means, the part 3, which may be conveniently called the mov-

- able back, of the drag or concave 2, carries the matrix. The part 3 is movable backwardly or away from casting position relatively to the remainder of the concave 2. 5 For this purpose part 3 is mounted in suitable guides in the concave 2, and is provided upon the exterior of the central back part thereof with lugs 48 and 49, which are apertured to receive a wrist pin 50. 10 Pivottally connected to the wrist pin 50 is an eccentric strap 51, mounted peripherally upon an eccentric 52, which eccentric is sleeved loosely on shaft 10. Fixed to or integral with the eccentric 52 is an arm 53, 15 pivoted by a link 54 to an arm 55. Arm 55 is fixed to or integral with a sleeve 57, loosely mounted on the shaft 20. The link 54 is preferably provided with an adjustment, such as a turn-buckle 56. 20 Fixed to or integral with the sleeve 57, is a hand lever 58, provided with a latch lever 59, pivoted upon the lever 58 at 60, and having a latch 61 adapted to engage, as lever 58 is moved, at various points along a toothed 25 sector 62, carried by a plate 63 fastened by suitable means, such as bolts 64 to the machine frame.
- To effect the automatic stripping of the matrix *y* from the plate *x* when the back 3 recedes, the back 3 is provided with matrix clamping jaws 69 and 70, which are spring-pressed and hold the matrix *y* along its straight edges, in the usual manner. The clamping jaws are pivoted respectively at 30 71 and 72 upon the back member 3 and when the back member is retracted from casting position, these jaws by their spring action are adapted to swing the matrix and strip it away from the cast plate. The details of 35 construction of the automatically acting matrix carrying jaws 69 and 70 are not shown herein, but may be generally similar to those shown in application Ser. No. 408- 203, of Albert A. Henzi, filed September 4, 40 1920.
- In the operation of the foregoing mechanism, the parts are shown in Figs. 6 and 7, in casting position and in retracted position, respectively, and in Fig. 6 the movable back 50 3 is at casting position as well as the concave 2. By rocking the hand lever 58 from the position of Fig. 6 to that of Fig. 7, eccentric 52 is rotated and the movable back 3 is retracted or moved backwardly 55 relatively to the concave member 2, and the matrix *y* stripped from the plate *x* as described, preparatory to and immediately preceding the recession of the drag 2 and the rotation of the core 1. 60
- In accordance with certain features of the invention, the plate *x* after casting is moved or delivered in the axial direction along the core 1 to bring it into relation with the tail cutting saws and into proper relation with 65 the delivery means prior to the rotation of

the core which carries the plate from casting position to the delivery position. In the embodied form of such means (Figs. 2, 4 and 10), the upper part of the core 1 is provided with an external portion or shell 81, which fits closely the internal portion 80 of the core 1, as will clearly be seen from Figs. 4 and 10. The external portion or shell 81 rotates with the remainder of the core, but is movable longitudinally of the core, 70 that is, in the axial direction thereof, and carries the plate with it in such movement. In the detailed exemplary construction, the shell 81 and the body 80 of the core are connected together by longitudinally disposed 75 keys 82, fitting into recesses formed in the contacting surface of both the shell 81 and the body 80 of the core.

Referring further to the details of structure, the core 1, in addition to having a bearing upon the machine base 83, is journaled on a shaft 84, extending upwardly from the machine base within the core. At its upper end shaft 84, (Fig. 4) has a shoulder 85 over which fits a hub or sleeve 86 formed on the head of the part 80 of core 1. The shell 81 has a conical upper portion 87, connected to a sleeve 89, so that the shell 81 is free to rotate with core 1 relatively to the sleeve 89, but the sleeve 89 and shell 81 will have longitudinal or axial movement together relatively to the core 1.

For this purpose, bolts 88 fasten plates 90 an annular ring 90 to the part 87 of the shell 81, the plate or plates 90 engaging beneath an outwardly extending collar 91, fixed to or integral with the sleeve 89, and fitting beneath shoulders in the part 87 of the shell 81 (Fig. 4).

Means are provided for imparting longitudinal or axial movement to the sleeve 89, and thereby to the shell 81, the shell 81 being left free to later rotate with the core 1 in bringing the plate from the casting position to the delivery position. For this purpose, the sleeve 89 is journaled in the cross piece 94 of the machine frame, and is held against rotary movement by a spline 95 engaging with the sleeve and with the frame. Formed on the external cylindrical surface of the sleeve 89 is a square screw-thread 96, with which meshes an internal screw-thread formed within a sprocket wheel 97. The sprocket wheel 97 rests upon the frame piece 94, and is held in place, that is, from rising vertically by a bearing piece 98 supported on the top of the hub 86 of the core 1, and fastened thereto by suitable means such as a screw bolt 99.

Suitable means are provided for rotating the sprocket wheel 97 to impart the longitudinal or axial or lifting movement to the shell 81 and therewith to the newly cast plate. In the embodied form of said means,

an endless sprocket chain 100 runs about the sprocket wheel 97 and about a sprocket wheel 101, which wheel is fixed on a shaft 102 and has a face or hub bearing 5 at 103 upon the machine frame. The shaft 102 is mounted in bearings 104, 105, 106 and 107 on the machine frame. Near the lower end of shaft 102 and just above the bearing 107, an arm 108 is keyed to the 10 shaft 102, its hub resting upon the bearing 107. Pivotally connected to the outer end of the arm 108 is a rod 109.

Rod 109 at its opposite end is pivotally connected to a lever 110, which lever is 15 pivoted at 111 upon the machine frame. At its opposite end, lever 100 is provided with a cam roller 112, which works in a box cam 113. Cam 113 is formed in a plate 114, which plate is fixed on the shaft 20 to 20 oscillate or swing therewith.

When the shaft 20 is rocked by means of any of the arms 21, 22 or 41, the cam plate 114 is rocked between the positions shown in Figs. 1 and 2, thereby rocking lever 110. This rocks arm 108, which imparts rotary movement to shaft 102, and sprocket wheels 101 and 97, the rotation of sprocket wheel 97 imparting longitudinal movement to the sleeve 89, and therewith 25 to the plate carrying shell 81 and to the plate α carried thereby.

Thus when the drag or concave 2 is swung down from the casting position of Fig. 1 to the delivery position of Fig. 2, the shell 30 81 is lifted and therewith the plate α , the plate being thereafter rotated to delivery position with the core 1. As the drag 2 is swung backwardly again from the position of Fig. 2 to that of Fig. 1 preparatory 35 to casting, through the mechanism just described, sprocket wheel 97 is rotated in the opposite direction, and the shell 81 descends again to the position for casting ready for the casting of the next plate.

40 For the purpose of carrying the cast plate with the shell 81, the latter is provided with recesses adapted to form slight projections upon the tail or riser of the plate, and such recesses 117 are provided designed 50 to insure rotary movement of the plate with the core, the axial or longitudinal movement of the plate with the core being effected by the conical conformation of the upper part of the shell 81.

55 Means are provided for holding the core in casting position, and for releasing it for rotary movement in proper sequence with the remainder of the mechanism. As embodied, said means (Figs. 3, 4, 5 and 11) 60 are controlled and operated from the means for moving the concave or drag 2 to and from the casting position. In such embodied form, recesses 124 are formed in the base of the core 1 (Fig. 3), and cooperating 65 therewith is a spring-operated detent 125

70 mounted in a bearing block 126 for longitudinal movement therein, the detent being acted on by a spring 127 within the block. The detent 125 at its outer end 128 is pivotally connected to a lever arm 129, which is 75 fixed to a shaft 130, journaled in bearings 122 and 123 on the machine frame. Fixed also to shaft 130 is an arm 131. Pivoted at 132 to arm 131 is a longitudinally slideable rod 133, slideable in bearings 134 and 135, 80 mounted on the machine frame.

The rod 133 is acted on by a spring 137, 85 fixed at one end 138 to the machine frame and at the other end 139 to the rod 133, thereby impelling the detent 125 resiliently 90 into engaging position with the recess 124 in the core 1. For the purpose of retracting the detent 125 to release the core 1, rod 133 is provided with a hook 140 at the end thereof. On the hub 141 of arm 21 95 is mounted a spring-actuated detent tooth 142, slideably mounted in a bearing block 143, which is fixed to the hub 141 by screw bolts 144. The detent 142 is acted on by spring 145 in compression between a shoulder on the detent tooth 142 and the bottom of the recessed interior of the block 143.

When the arm 21 is swung upwardly in 100 Figs. 2 and 11, to move the concave or drag 2 from casting position, the tooth 142 will engage the hook 140 and draw rod 133 to the left in Fig. 11, that is, to the right in Fig. 3, thereby withdrawing the detent 125 from the recess 124 and leaving the core 1 free to rotate. As the arm 21 continues to 105 rotate from the position shown in Figs. 1 and 11 to that shown in Fig. 2, the detent tooth 142 will arc out of the hook 140, and spring 137 will pull back rod 133. This will cause detent 125 to press against cylinder 1 and to be ready to snap into the recess 124 in the core 1 as it comes around and will again arrest the core 1 in proper casting position.

110 The embodied form of means for intermittently rotating the core 1, to bring the successively cast plates from casting position to delivery position, comprises a worm wheel 155 formed on the base of the core 1, with which meshes a worm 156 (Figs. 1, 3 and 4). Worm 156 is fixed on a sleeve 157, which sleeve is loose on a shaft 158, the shaft being journaled in bearings 159 and 160 mounted upon the machine frame. Fixed to the sleeve 157 is a clutch member 162, adapted to cooperate with a clutch member 163, which is fixed on the shaft 158 115 to rotate therewith by suitable means, such as a pin 164 passing through the hub of the clutch member 163.

120 The clutch members 162 and 163 are yieldingly impelled into engagement by suitable means, and as embodied a spring 165 is coiled about shaft 158 and is in compression between the sleeve 157 and a collar 125

166, fixed on shaft 158. To drive shaft 158, there is fixed thereon a worm wheel 170, with which meshes a worm 171, which is keyed to a shaft 172. Shaft 172 is journaled in bearings 173 and 174, mounted on the machine frame, and is rotated by any suitable means. As herein shown, a belt pulley 175 is fixed on shaft 172, over which runs a belt 176, running over pulley 177, fixed on the shaft of a motor 178.

The shaft 172 is preferably continuously driven, and the shaft 158 is likewise preferably continuously driven therefrom. The detent 125 may be regarded as withdrawn from the recess 124 in the core 1, and the core 1 is free to rotate. The spring 165 impels the clutch jaw 162 into engagement with the clutch jaw 163, thereby rotating the worm 156 from shaft 158, thereby through the worm wheel 155 rotating the core 1. When the core 1 has made a semi-rotation, detent 125 engages the recess 124, and stops the rotation of the core 1. This stops the rotation of the worm 155, and clutch member 163 continuing to rotate with shaft 158, clutch member 162 is forced out of engagement with clutch member 163, against the action of spring 165.

Means are provided for cutting off the tail or riser from the cast plate α , and in the embodied form (Figs. 3, 4 and 12) of such means, a beveled gear 185 is fixed on shaft 172. Meshing with beveled gear 185 is a beveled gear 186, which is mounted loosely on shaft 102. Fixed to the hub of beveled gear 186 is a sprocket wheel 187, over which runs a sprocket chain 188, which also runs over a sprocket wheel 189, fixed on a shaft 190.

Shaft 190 is journaled in bearings 191 and 192 carried on a swinging bracket comprising arms 193 and 194 fixed to a sleeve 195, which sleeve is loosely journaled on shaft 102 between the bearing 105 and 106, and resting upon the latter bearing. Shaft 190 is provided with a collar 196, cooperating with the journal bearing 192 to hold the shaft in longitudinal position. The shaft is provided at its upper end with a saw or cutter 197, which rotates with the shaft 190, its hub 198 resting upon the journal sleeve 191.

Means are provided for moving the saw 197 into and out of cutting position with respect to the cast plate. In accordance with one feature of the invention such movement of the saw is automatic and is effected by the mechanism which swings the drag 2 back from casting position and starts the core 1 in its rotary motion. As embodied (Figs. 1, 3, 4 and 12), a rod or connecting link 200 is pivoted at 201 to the bracket arm 193 of the support for saw 197. At its other end 202 the link or rod 200 is pivoted to a lever 203, which lever is pivotally mounted at 204 upon the machine frame.

At its opposite end lever 203 is provided with a cam roller 205 working in a box cam 206 formed in a cam plate 207, which plate is fixed on shaft 20.

Thus as the shaft 20 is rocked to swing the drag 2 back from casting position, and just prior to the beginning of the rotary motion of the core 1, the saw 197 is swung into position to engage with the plate α , and as the core 1 rotates to saw off the riser. When shaft 20 is rotated in the opposite direction to bring the drag 2 back to casting position, the saw 197 is swung backwardly to the disengaging position, as shown in Fig. 12. The saw may be proportioned to project slightly into the space left between core 80 and sleeve 81 and thus will entirely and cleanly sever the plate from the tail.

The delivery station is shown in Figs. 1, 2, 3 and 12, and comprises a platform 210, with the inner edge abutting on the core 1 of arcuate form to conform to the shape of the core. The platform 210 is vertically adjustable, and for this purpose is provided with recessed sides to take guides 211 and 212, formed respectively on posts 213 and 214. The platform 10 is provided with depending portions, through which pass respectively bolts 215 and 216, which bolts pass through slots 217 in the posts 213 and 214, thereby providing vertical adjustment for the plate receiving platform 210.

The manner of operation of the various mechanisms has been described in connection with the detailed description of the structure of the various parts, but a brief summary will be given as follows:

The drag 2 may be regarded as in the casting position, as shown in Fig. 1, and a plate may be regarded as just having been cast. After the plate is so cast, lever 58 is swung from the position of Fig. 6 to that of Fig. 7, and the matrix carrying back 3 is thereby retracted, and the spring clamps 69 and 70 are thereby caused to strip the matrix from the cast plate. One of the levers 21, 22 or 41 is swung from the position of Fig. 1 to that of Fig. 2, thereby retracting the drag 2 from casting position as shown in Fig. 1 to the position of Fig. 2.

When the drag is swung back in the manner described, cam plate 114 rocks with shaft 20, and lever 110 is actuated, thereby imparting rotation to shaft 102, and the shell 81 is raised vertically and therewith the plate α which has just been cast.

The swinging of arm 21 has retracted detent 125 from the recess 124, releasing core 1, which is then rotated through worm wheel 155 and worm 156 for a half rotation bringing the cast plate to the delivery position.

Also when shaft 20 is rocked, cam plate 207 rocks therewith, and swings the saw 197 from the position of Fig. 12 to the po-

sition of Figs. 3 and 4, thereby cutting off the tail or riser from the plate. As the semi-revolution of core 1 is completed, detent 125 enters a recess 124 in the core 1, and brings 5 the core to rest with the cast plate at the delivery position, the clutch 162, 163 being thrown out. The machine is now in position for casting the next plate, whereupon the operations as herein described are 10 repeated. If the lever 58 be left in the position shown in Fig. 6 and the casting box be opened, the matrix carrying back 3 will simultaneously recede automatically and the matrix will be thereby stripped automatically. This manner of operation may be 15 optionally employed instead of preliminarily receding the back as already described.

The bottom of the casting chamber is formed in the present instance by the horizontal projection from the core just above the worm wheel 155 and may be regarded as the upper flat face of the worm wheel. The straight vertical sides of the casting chamber are formed by the edges of the matrix clamps 69 and 70 opposite the plate and by like parts formed on the core or the sleeve 25 81 opposite the tail of the plate.

In Fig. 13 a form of rib 80^a on the casting device is shown designed to especially 30 facilitate the removal of the plate in the axial direction of the core, although the ordinary or other suitable form of rib may be employed if desired.

Suitable cooling means for the core of any 35 standard or suitable type or kind may be provided, but are not shown herein, and the same may be provided for the drag also if desired.

The invention in its broader aspects is 40 not limited to the specific mechanisms shown and described but departures may be made therefrom within the scope of the accompanying claims without departing from the principles of the invention and without 45 sacrificing its chief advantages.

What I claim is:—

1. A stereotype plate casting machine including in combination a core, and a drag made in two relatively movable parts, constituting a casting chamber, and means for stripping the matrix from the cast plate while said core, and one part of the drag remain in casting position.

2. A stereotype plate casting machine including in combination a core, and a drag made in two relatively movable parts, constituting a casting chamber, one at least of said members being movable from casting position, means for stripping the matrix from the cast plate while said core, and one part of the drag remain in casting position, and means for moving said movable member from casting position after the matrix is stripped from the plate.

3. A stereotype plate casting machine in-

cluding in combination a core, and a drag made in two relatively movable parts, constituting a casting chamber, and manually operable means for stripping the matrix from the cast plate while said core, and one part of the drag remain in casting position.

4. A stereotype plate casting machine including in combination a core, and a drag made in two relatively movable parts, constituting a casting chamber, one at least of said members being movable from casting position, means for stripping the matrix from the cast plate while said core, and one part of the drag remain in casting position, and means for moving said movable member in a vertically disposed arcuate path from casting position after the matrix is stripped from the plate.

5. A stereotype plate casting machine including in combination a core, and a drag made in two relatively movable parts, constituting a casting chamber, one at least of said members being movable from casting position, manually operable means for stripping the matrix from the cast plate while said core, and one part of the drag remain in casting position, and means for moving said movable member from casting position after the matrix is stripped from the plate.

6. A stereotype plate casting machine including in combination a core, and a drag made in two relatively movable parts, constituting a casting chamber, one at least of said members being movable from casting position, means for stripping the matrix from the cast plate while said core, and one part of the drag remain in casting position, and manually operable means for moving said movable member from casting position after the matrix is stripped from the plate.

7. A stereotype plate casting machine including in combination a core, and a drag made in two relatively movable parts, constituting a casting chamber, one at least of said members being movable from casting position, manually operable means for stripping the matrix from the cast plate while said core, and one part of the drag remain in casting position, and manually operable means for moving said movable member from casting position after the matrix is stripped from the plate.

8. A stereotype plate casting machine including in combination members constituting a casting chamber, one of said members having a relatively movable matrix carrying part, and means for moving said matrix carrying part away from casting position while said member is at casting position.

9. A stereotype plate casting machine including in combination members constituting a casting chamber, one of said members having a relatively movable matrix carrying part, and manually operable means for moving said matrix carrying part away

from casting position while said member is at casting position.

10. A stereotype plate casting machine including in combination members constituting a casting chamber, one of said members having a relatively movable matrix carrying part, means for moving said matrix carrying part away from casting position while said member is at casting position, and matrix holding and stripping clamps mounted on said relatively movable part, said clamps operating to strip the matrix from the plate when said part is moved away from casting position.

15. 11. A stereotype plate casting machine including in combination members constituting a casting chamber, one of said members having a relatively movable matrix carrying part, means for moving said matrix carrying part away from casting position while said member is at casting position, and automatically operating matrix holding and stripping clamps mounted on said relatively movable part, said clamps operating to strip the matrix from the plate when said part is moved away from casting position.

20. 12. A stereotype plate casting machine including in combination members constituting a casting chamber, one of said members having a relatively movable matrix carrying part, means for moving said matrix carrying part away from casting position while said member is at casting position, and automatically operating spring actuated matrix holding and stripping clamps mounted on said relatively movable part, said clamps operating to strip the matrix from the plate when said part is moved away from casting position.

25. 13. A stereotype plate casting machine including in combination members constituting a casting chamber, one of said members having a relatively movable matrix carrying part, manually operable means for moving said matrix carrying part away from casting position while said member is at casting position, and automatically operating spring actuated matrix holding and stripping clamps mounted on said relatively movable part, said clamps operating to strip the matrix from the plate when said part is moved away from casting position.

30. 14. A stereotype plate casting machine including in combination members constituting a casting chamber, one of said members having a relatively movable matrix carrying part, means for moving said matrix carrying part away from casting position while said member is at casting position, and means for opening the casting chamber after the matrix is stripped.

35. 15. A stereotype plate casting machine including in combination a core, and a drag made in two relatively movable parts, constituting a casting chamber, means for strip-

ping the matrix from the cast plate while said core, and one part of the drag remain in casting position, and means for opening the casting chamber after the matrix is stripped.

40. 16. A stereotype plate casting machine including in combination members constituting a casting chamber, one of said members having a relatively movable matrix carrying part, means for moving said matrix carrying part away from casting position while said member is at casting position, matrix holding and stripping clamps mounted on said relatively movable part, said clamps operating to strip the matrix from the plate when said part is moved away from casting position, and means for opening the casting chamber after the matrix is stripped.

45. 17. A stereotype plate casting machine including in combination members constituting a casting chamber, one of said members having a relatively movable matrix carrying part, means for moving said matrix carrying part away from casting position while said member is at casting position, and means for moving said member away from casting position after the matrix is stripped.

50. 18. A stereotype plate casting machine including in combination members constituting a casting chamber, one of said members having a relatively movable matrix carrying part, means for moving said matrix carrying part away from casting position while said member is at casting position, matrix holding and stripping clamps mounted on said relatively movable part, said clamps operating to strip the matrix from the plate when said part is moved away from casting position, and means for moving said member away from casting position after the matrix is stripped.

55. 19. A stereotype plate casting machine including in combination a vertically disposed core, a drag cooperating therewith, means for retaining the cast plate on the core, means for rotating the core, and means for moving the drag from casting position through a vertically disposed arcuate path.

60. 20. A stereotype plate casting machine including in combination a vertically disposed core, a drag cooperating therewith, automatically operating means for rotating the core, and manually operable means for moving the drag from casting position through a vertically disposed arcuate path.

65. 21. A stereotype plate casting machine including in combination a vertically disposed core, a drag cooperating therewith, automatically operating means for rotating the core, manually operable means for moving the drag from casting position through a vertically disposed arcuate path, and said automatically operable core rotating means being called into action by the actuation of the drag moving means.

22. A stereotype plate casting machine including in combination a vertically disposed core, a drag cooperating therewith, automatically operating means for rotating the core, means for moving the drag from casting position through a vertically disposed arcuate path, and said core rotating means being called into action by the actuation of the drag moving means.
23. A stereotype plate casting machine including in combination a vertically disposed core, a drag cooperating therewith, means for rotating the core, means for holding the core from rotating, means for moving the drag from casting position through a vertically disposed arcuate path, and means for releasing the core and calling the core rotating means into operation when the drag moving means are operated.
24. A stereotype plate casting machine including in combination a casting chamber comprising a core and a drag, and means for moving the cast plate longitudinally of and in contact with the stationary core.
25. A stereotype plate casting machine including in combination a casting chamber comprising a core and a drag, means for moving the drag away from casting position, and means for moving the cast plate along the core.
26. A stereotype plate casting machine including in combination a casting chamber comprising a core and a drag, means mounted on the core for moving the cast plate longitudinally of the core, and means for rotating the core.
27. A stereotype plate casting machine including in combination a casting chamber comprising a core and a drag, means for moving the drag away from casting position, means for moving the cast plate longitudinally of while retaining it upon the core, and means for rotating the core.
28. A stereotype plate casting machine including in combination a casting chamber comprising a core and a drag, means mounted on the core for moving the cast plate longitudinally of the stationary core, and means for subsequently rotating the core.
29. A stereotype plate casting machine including in combination a casting chamber comprising a core and a drag, and automatically operating means mounted on the core for moving the cast plate longitudinally of the core.
30. A stereotype plate casting machine including in combination a casting chamber comprising a core and a drag, means for moving the drag away from casting position, and means mounted on the core for moving the cast plate longitudinally of the core.
31. A stereotype plate casting machine including in combination a casting chamber comprising a core and a drag, means mount-
- ed on the core for moving the cast plate longitudinally of the stationary core, and automatically operating means for rotating the core.
32. A stereotype plate casting machine including in combination a casting chamber comprising a core and a drag, means mounted on the core for moving the drag away from casting position, means for moving the cast plate longitudinally of and only partly along the core, and automatically operating means for rotating the core carrying the plate.
33. A stereotype plate casting machine including in combination a casting member comprising a core and a drag, means mounted on the core for moving the cast plate longitudinally of without removing it from the core, and automatically operating means for subsequently rotating the core carrying the plate.
34. A stereotype plate casting machine including in combination a casting chamber comprising a core and a drag, means for moving the drag away from casting position, and means called into action by moving the drag from casting position for moving the plate longitudinally of the core.
35. A stereotype plate casting machine including in combination a casting chamber comprising a core and a drag, means for moving the drag away from casting position, and automatically operating means called into action by moving the drag from casting position for moving the plate longitudinally of the core.
36. A stereotype plate casting machine including in combination a casting chamber comprising a core and a drag, means for moving the drag away from casting position, means called into action by moving the drag from casting position for moving the plate longitudinally of the core, and means for rotating the core called into operation by moving the drag from casting position.
37. A stereotype plate casting machine including in combination a casting chamber comprising a core and a drag, means for moving the drag away from casting position, means called into action by moving the drag from casting position for moving the plate longitudinally of the core, and automatically operating means for rotating the core called into operation by moving the drag from casting position.
38. A stereotype plate casting machine including in combination a casting chamber comprising a core and a drag, manually operable means for moving the drag away from casting position, and means called into action by moving the drag from casting position for moving the plate longitudinally of the core.
39. A stereotype plate casting machine including in combination a casting chamber

comprising a core and a drag, manually operable means for moving the drag away from casting position, and automatically operating means called into action by moving the drag from casting position for moving the plate longitudinally of the core.

40. A stereotype plate casting machine including in combination a casting chamber comprising a core and a drag, manually operable means for moving the drag away from casting position, means called into action by moving the drag from casting position for moving the plate longitudinally of the core, and means for rotating the core called into operation by moving the drag from casting position.

41. A stereotype plate casting machine including in combination a casting chamber comprising a rotatable core which carries the plate away from casting position, the core having an annular encircling recess, and a saw cutting the tail from the plate at said recess while the core rotates.

42. A stereotype plate casting machine including in combination casting means comprising a core, a saw and means for creating a saw-receiving depression in the core preparatory to the saw cutting off the tail of the plate.

43. A stereotype plate casting machine including in combination casting means comprising a core, a saw and means for moving a part of the core, thereby creating a saw-receiving depression in the core preparatory to the saw cutting off the tail of the plate.

44. A stereotype plate casting machine including in combination casting means comprising a vertically disposed core, a saw and means for creating a saw-receiving depression in the core preparatory to the saw cutting off the tail of the plate.

45. A stereotype plate casting machine including in combination casting means comprising a core, a saw and means for moving one end of the core, thereby creating a saw-receiving depression in the core preparatory to the saw cutting off the tail of the plate.

46. A stereotype plate casting machine including in combination casting means comprising a vertically disposed core, a saw and means for moving the upper end of the core,

thereby creating a saw-receiving depression in the core preparatory to the saw cutting off the tail of the plate.

47. A stereotype plate casting machine including in combination casting means including a core, a saw, means for making a saw-receiving depression in the core after the plate is cast into which the saw projects while cutting off the tail from the plate.

48. A stereotype plate casting machine including in combination casting means including a core, a saw, means for making a saw-receiving depression in the core after the plate is cast into which the saw projects while cutting off the tail from the plate, and means for moving the core to convey the trimmed plate to a place of delivery.

49. A stereotype plate casting machine including in combination casting means including a cylindrical core, a saw, means for making a cylindrical saw-receiving depression in the core after the plate is cast into which the saw projects while cutting off the tail from the plate.

50. A stereotype plate casting machine including in combination casting means including a cylindrical core, a saw, means for making a cylindrical saw-receiving depression in the core after the plate is cast into which the saw projects while cutting off the tail from the plate, and means for moving the core to convey the trimmed plate to a place of delivery.

51. A stereotype plate casting machine including in combination casting means comprising a multipart core, one of said parts having means for engaging with the plate, and means for effecting relative movement between said parts to effect relative movement between one of said parts and the plate.

52. A stereotype plate casting machine including in combination casting means comprising a multipart core, one of said parts having means for engaging with the plate, and means for effecting relative movement between said parts to create a saw-receiving opening therebetween and a saw for sawing the plate at said opening.

In testimony whereof, I have signed my name to this specification.

ERNEST J. SMITH.
